UNITED STATES PATENT OFFICE.

FRANK A. MITCHELL, OF WASHINGTON, DISTRICT OF COLUMBIA.

ROOFING COMPOUND.

SPECIFICATION forming part of Letters Patent No. 707,710, dated August 26, 1902.

Application filed December 10, 1901. Serial No. 85,397. (No specimens.)

To all whom it may concern:

Be it known that I, FRANK A. MITCHELL, a citizen of the United States, residing at Washington, in the District of Columbia, have invented certain new and useful Improvements in Roofing Compounds; and I do hereby declare the following to be a full, clear, and exact description of the invention, such as will enable others skilled in the art to which it applies to make and use the same.

My invention relates to roofing compositions; and it consists in a certain combination of elements whereby a more durable and advantageous roofing composition is produced. The combination of elements comprised in my said improved composition is of the materials and in the proportions following: three hundred pounds of bolted slate-powder; two hundred pounds of powdered soapstone; fifty gallons of coal-tar; one gallon sour milk, and one quart creosotine.

In making the roofing the coal-tar is first heated, the bolted slate-flour and powdered soapstone is then added and thoroughly mixed, after which the other ingredients are

added to the mixture and thoroughly mingled and incorporated therewith. By this means a pasty mass is produced or a mass of the consistency of thin mortar, which may be readily applied to roofs in the usual manner. The roofing made from this composition is of a thoroughly homogeneous character and of great durability.

The substance designated "creosotine" is a product of the distillation of coal-tar. It is a liquid and is known in the trade by the name "creosotine."

What I claim, and desire to secure by Letters Patent, is—

The herein-described roofing composition of bolted slate-flour, powdered soapstone, coal-tar, sour milk and creosotine in the proportions, substantially as specified.

In testimony whereof I affix my signature in the presence of two witnesses.

F. A. MITCHELL.
